(57) **CLAIM**

The ornamental design for a bottle, as shown and described.

DESCRIPTION

FIG. 1 is a top, front, left side perspective view of a bottle according to a first embodiment of our new design;

FIG. 2 is a front elevational view thereof;

FIG. 3 is a rear elevational view thereof;

FIG. 4 is a left side elevational view thereof;

FIG. 5 right side elevational view thereof;

FIG. 6 is a top plan view thereof;

FIG. 7 is a bottom plan view thereof;

FIG. 8 is a top, front, left side perspective view thereof, shown with an unclaimed spray pump, nozzle, and cap;

FIG. 9 is a top, front, left side perspective view thereof; shown with an exploded view of the spray pump, nozzle, and cap;

FIG. 10 is a top, front, left side perspective view of a bottle according to a second embodiment of our new design;

FIG. 11 is a front elevational view thereof;

FIG. 12 is a rear elevational view thereof;

FIG. 13 is a left side elevational view thereof;

FIG. 14 right side elevational view thereof;

FIG. 15 is a top plan view thereof; and,

FIG. 16 is a bottom plan view thereof.

The oblique line shading represents transparency.

The broken lines shown in the drawing views are included for the purpose of illustrating environmental structure that forms no part of the claimed design.
